PNEUMATIC GUN

William S. Wells, Palo Alto, Calif., assignor to
 Daisy Manufacturing Company, Plymouth,
 Mich., a corporation of Michigan

Application December 24, 1947, Serial No. 793,676

2 Claims. (Cl. 124—13)

1

This invention relates generally to guns and refers more particularly to guns of the type wherein shot is propelled through the barrel by air under pressure.

Guns of the above type are usually equipped with a storage chamber containing air under sufficient pressure to propel shot either of the ball or pellet type through the barrel at high velocities. The air in the storage chamber is periodically replenished by a compressor either incorporated as a part of the gun or forming a separate unit attachable to the gun whenever it is necessary to replenish the air in the chamber. In either case the flow of air under pressure from the storage chamber to the gun barrel is controlled by a valve operated by manipulation of suitable trigger mechanism.

One serious objection to many types of pneumatic guns heretofore employed is the necessity of replenishing the supply of air in the storage chamber after practically each shot in order to obtain anything like uniform velocity of successive shots. In most pneumatic guns the mechanism is such that the first shot subsequent to replenishing the storage chamber moves at considerable velocity due to the relatively high air pressure existing in the chamber. However, the drop in pressure in the chamber after the first shot is so severe that the second shot is discharged at a considerably less velocity and in most instances, the air pressure in the chamber must be restored before the third shot is discharged. The necessity of replenishing the air pressure in the storage chamber at such frequent intervals is inconvenient and requires considerable time.

With the above in view, it is an object of this invention to provide a pneumatic type gun characterized in that a relatively large number of shot or pellets may be discharged at a substantially uniform velocity without replenishing the storage chamber. The number of shots obtainable with one air charge depends upon the velocity of the shots, but regardless of whether a small or a relatively large number of shots are required, the velocity of successive shots is generally uniform.

A more detailed object of this invention is to provide a pneumatic gun wherein the air pressure required to propel shot through the gun barrel is obtained from a receiving chamber having a fluid connection with a storage chamber through a pressure regulating valve assembly. The valve assembly maintains a substantially uniform air pressure in the receiving chamber

2

which is considerably lower than the air pressure in the storage chamber, but is sufficient to propel shot through the barrel at the required velocity. Thus successive shots are propelled through the gun barrel at practically the same velocity until the pressure in the storage chamber approaches the pressure in the receiving chamber or until the storage chamber pressure drops below the pressure at which the valve will operate to transfer fluid pressure from the storage chamber to the receiving chamber.

Another object of this invention is to provide a pressure regulating valve having a slideable valve member held in a position wherein communication between the two chambers is closed by the pressure of the fluid in the receiving chamber and having spring means for moving the valve member to establish communication between the chambers in response to a drop in pressure in the receiving chamber below a predetermined value.

Still another object of this invention is to provide a valve assembly wherein the surface area of the valve member exposed to the fluid pressure in the receiving chamber exceeds the area of the valve surface exposed to the pressure existing in the storage chamber by an amount such that the valve member is held in its closed position against the action of the spring means by a predetermined pressure in the receiving chamber which is substantially less than the pressure in the storage chamber.

A further object of this invention is to control the flow of fluid under pressure from the receiving chamber to the gun barrel with a valve normally held in its closed position by the fluid under pressure in the receiving chamber and adapted to be momentarily opened by a trigger operated hammer.

The foregoing as well as other objects will be made more apparent as this description proceeds, especially when considered in connection with the accompanying drawing, wherein:

Figure 1 is a fragmentary sectional view through a pneumatic gun embodying the features of this invention;

Figure 2 is an enlarged sectional view through the pressure regulating valve provided between the storage chamber and receiving chamber on the gun; and

Figure 3 is a cross sectional view taken on the line 3—3 of Figure 1.

Although this invention may be advantageous-
 55 ly used in connection with pneumatic guns of

various different types, nevertheless, for the purpose of illustration, I have shown a pneumatic gun of the general type disclosed in my co-pending application, Serial No. 762,391 filed July 21, 1947 (now abandoned). Briefly, the gun comprises a stock 11 and a frame 12 suitably removably secured to the stock by fastener elements 13. The frame 12 comprises a barrel 14, a storage chamber 15 and a receiving chamber 16 communicating with the storage chamber through the medium of a pressure regulating valve 17.

The barrel 14 is axially bored to receive shot either of the pellet or ball type, and is formed with an opening 18 at the breech end thereof through which the shot may be inserted into the barrel. Although either ball or pellet type shot may be employed, nevertheless, pellet type shot is preferred for most satisfactory operation, and the numeral 19 in Figure 1 of the drawing designates a shot of the pellet type. In accordance with conventional practice, the pellet 19 is formed with a relatively thin skirt portion 20 at the trailing end which flares outwardly to a maximum normal diameter somewhat greater than the internal diameter of the bore in the gun barrel. Thus when the pellet 19 is inserted into the bore, the skirt portion 20 is contracted, and intimately engages the inner surface of the gun barrel throughout its circumference to form an effective seal behind the pellet. Actually the skirt portion 20 is so thin that the pressure of the propelling air introduced into the barrel behind the pellet tends to expand the skirt outwardly against the inner surface of the barrel. As a result leakage of air under pressure past the pellet is reduced to a minimum, and the full force of this air is applied to the pellet for discharging the same from the barrel.

The storage chamber 15 is positioned directly below the barrel 14, in advance of the receiving chamber 16, and is separated from the latter by a partition 21. The front end of the storage chamber 15 is open to receive a suitable hand operated compressor 22, and is internally threaded for threadably engaging the adjacent portion of the compressor cylinder 23. The rear end of the storage chamber 15 is formed with an outlet port 25, and the latter communicates with the receiving chamber 16 through the pressure regulating valve 17 in a manner to be presently described.

The receiving chamber 16 is located directly in rear of the storage chamber 15, and is open at the rear end to a passage 26 having a vertical extension 27 communicating with the bore in the gun barrel in advance of the shot receiving opening 18. Formed on the rear wall of the receiving chamber 16 and surrounding the entrant end of the passage 26 is a flat seat 28 for engagement with a valve 29. The valve 29 comprises a plunger 30 slidably supported in a tubular guide 31 and having a pad 32 of wear resisting deformable material secured to the rear end thereof in a position to engage the seat 28. The tubular guide 31 is secured at its front end to the partition 21 and is formed with an opening 33 in the side wall thereof to enable fluid under pressure to flow into the tubular guide at the front end of the plunger 30. Thus the air under pressure in the receiving chamber serves to hold the plunger 30 in its rearwardmost position wherein the passage 26 is closed by engagement of the pad 32 with the valve seat 28. In the present instance a relatively weak coil spring 34 is supported in the tubular guide 31 between the partition 21 and the

valve plunger 30 for yieldably positioning the pad 32 against the seat 28.

The receiving chamber 16 is formed with an inlet port 35 adapted to be connected to the outlet port 25 in the storage chamber through the pressure regulating valve 17. The pressure regulating valve 17 comprises a casing 36 and a valve member 37 slidably supported in the casing 36. The casing 36 is secured on the frame 12 of the gun directly below the receiving chamber 16, and is closed at the rear end by a plug 38. The front end of the casing is closed by a wall 39 having a tubular guide 40 extending rearwardly therefrom in concentric relation to the axis of the casing and adapted to slidably support the valve member 37 with the outer surface of the valve member spaced from the adjacent wall of the casing to form an annular passage 41 around the valve member.

As shown particularly in Figure 2 of the drawing, the valve member 37 is preferably formed of rubber or synthetic rubber, and is provided with a bore 42 extending rearwardly from the front end of the member to a point intermediate the ends thereof. The internal diameter of the bore is predetermined to provide a sliding fit between the valve member and guide which is sufficiently close to prevent leakage of fluid along the guide. It will further be noted that the valve member 37 has a projection 43 which extends axially forwardly into the tubular guide and forms an annular shoulder for engagement with the rear end of a coil spring 44. The front end of the coil spring is engageable with an adjustable plug 45 threadably supported in an opening formed through the front wall 39 of the casing in alignment with the tubular guide 40. The purpose of the coil spring 44 is to yieldably urge the valve member 37 in a rearward direction to engage the rear wall 43 of the valve member with an abutment 45 projecting forwardly from the plug 38.

A port 46 is formed in the casing 36 for connecting the outlet port 25 to the interior of the casing 36 at the front end of the valve member 37. It will be noted that the port 46 communicates with the casing radially outwardly beyond the tubular guide 40, and is adapted to be closed by the front end of the valve member when the latter is in its forwardmost position. It will further be observed from Figure 2 of the drawing that an outlet port 47 is formed in the casing at the rear end of the latter for connecting the inlet port 35 of the receiving chamber to the annular passage 41 in the valve casing 36. Thus in the open position of the valve member 37 shown in Figure 1 of the drawing, the receiving chamber 16 is connected to the storage chamber 15 through the pressure regulating valve 17.

The purpose of the pressure regulating valve 17 is to maintain a substantially uniform pressure in the receiving chamber which is predetermined to exert the force on the pellet 19 required to discharge the same with the desired velocity. For the purpose of this description, let it be assumed that the storage chamber 15 contains a supply of air at approximately 500 p. s. i., and that the desired pressure in the receiving chamber 16 is 150 p. s. i. In order to maintain approximately 150 p. s. i. in the receiving chamber, the pressure regulating valve 17 is adapted to move to its open position to allow fluid under pressure to flow from the storage chamber to the receiving chamber when the pressure in the latter drops below 150 p. s. i. More particularly the area of the surface 43 at the rear end of the valve mem-

ber exposed to the pressure in the receiving chamber is so determined with respect to the relatively small area of the valve member exposed to the relatively high pressure in the storage chamber 15 that the valve member is held in its closed position against the action of the spring 44 by the relatively low pressure in the receiving chamber 16. However, as soon as the pressure in the receiving chamber drops below 150 p. s. i., the spring 44 overcomes the force exerted by the pressure in the receiving chamber on the surface 48 of the valve, and moves the valve member to its opening position against the projection 45. As a result fluid under pressure from the storage chamber enters the valve casing 36 through the port 46 and flows through the annular passage 41 to the receiving chamber 16. As soon as the pressure in the receiving chamber is built up to approximately the predetermined desired value, the force acting on the surface 48 of the valve member becomes sufficient to move the valve member against the action of the spring 44 to again close the port 46. In this connection it will be noted that a bleed passage 49 is formed in the plug 45' to prevent pressure from being built up within the tubular guide 40 upon forward movement of the valve member 37. It will also be noted that the plug 45' may be readily adjusted to vary the strength of the spring 44, and thereby enable obtaining practically any desired pressure in the receiving chamber below the existing pressure in the storage chamber.

It follows from the above that the pressure regulating valve will open automatically to replenish the receiving chamber from the storage chamber and maintain a predetermined pressure in the receiving chamber. As a result the force applied on successive shots in response to repeated operation of the valve 29 will be approximately uniform, and accordingly, successive shots will be discharged at practically the same velocity. As will be more fully hereinafter described, the valve 29 remains open for a very short period of time, with the result that a substantial number of shots may be discharged in succession from the barrel without replenishing the supply in the storage chamber 15.

However, when the pressure in the storage chamber 15 decreases to a value approximating the predetermined desired pressure in the receiving chamber, it may readily be replenished by manipulating the compressor 22. In general this compressor embodies a piston 50 slidably supported in the cylinder 23 and operatively connected to a manually operable plunger 51. The piston 50 has a passage 52 therethrough controlled by a valve member 53, which in turn, is secured to the rear end of the plunger 51. The arrangement is such that when the plunger 51 is moved outwardly, the valve member 53 is retracted from its seat, permitting air to flow through the passage 52 into the cylinder 23 at the rear end of the piston. On the other hand, when the piston is moved rearwardly, the valve member 53 closes the passage 52 and enables the piston to compress the air. This compressed air flows from the rear end of the cylinder 23 into the storage chamber 15 through a check valve 54 which operates to trap the compressed air in the storage chamber during movement of the compressor piston on its suction stroke.

The valve 29 is automatically operated in response to the manipulation of a trigger 60 supported for sliding movement on the gun frame in 75

accordance with conventional practice. Upon reference to Figure 1 of the drawing, it will be noted that a pin 61 is slidably mounted in a bore formed in the gun frame 12 in alignment with the passage 16 and having the front end portion abutting the pad 32 on the valve 29. The rear end of the pin is adapted to be engaged by an anvil 62 supported for sliding movement in a bore 63 formed in the breech end of the frame and secured to a guide rod 64. The guide rod 64 is supported for fore and aft sliding movement in a plug 65 closing the rear end of the bore 63, and a hammer 66 is slidably mounted on the rod 64. The hammer is normally urged toward the anvil by a coil spring 67 surrounding the guide rod 64 between the rear end of the hammer and the plug 65.

The hammer is normally held in its rearward-most position wherein the coil spring 67 is compressed by a sear 68 suitably pivotally supported on the frame 12 of the gun below the bore 63. The sear 68 is actuated by the trigger 60 through the medium of a bell crank lever 69 having one arm 70 engageable with the sear and having the other arm 71 engageable with the trigger. The sear 68 is normally urged by suitable spring means 72 to a position in engagement with the hammer 66 and is released from the hammer by movement of the trigger in a rearward direction. Of course, releasing the sear from the hammer enables the spring 67 to throw the hammer forwardly against the anvil 62, and the resulting impact is transmitted to the valve 29 by the pin 61. The force of the impact is predetermined to momentarily retract the valve member 32 from its seat against the action of the air pressure in the receiving chamber to permit a limited amount of air under pressure to enter the barrel in rear of the pellet 19. The air under pressure entering the barrel is sufficient to discharge the pellet from the barrel at the specified velocity. Immediately following the impact, the valve 29 is, of course, instantaneously closed by the substantial pressure in the receiving chamber, so that only a minimum amount of air is released during each successive operation of the valve 29.

50 The hammer 66 is returned to its cocked position by means of a slide 75 supported on the gun frame 12 at the breech end of the barrel for sliding movement and having a block 76 depending therefrom in the path of travel of the hammer 66. Attention is called to the fact that the construction is such that during retracting movement of the hammer by the slide 75, the opening 18 is exposed to enable a shot to be inserted into the barrel rearwardly of the passage 27. This shot is transferred to a position in advance of the passage 27 by a pin 77 slidably supported in the breech end of the barrel and connected to the block 76.

60 Thus from the foregoing, it will be observed that I have provided a pneumatic gun wherein a substantially constant supply of compressed air is available for a given number of successive shots, so that each shot is discharged from the barrel at practically the same velocity. It will further be noted that only a relatively small amount of air is released during each operation so that a considerable number of shots may be discharged from the gun without replenishing the supply in the storage chamber.

65 What I claim as my invention is:

1. A hand carriable self-contained pneumatic gun including a barrel through which shot is propelled, housing means including a chamber extending generally parallel to said barrel, means

separating said chamber into a storage chamber adapted to contain a supply of air under pressure and an adjacent receiving chamber communicable with said barrel, a normally closed valve controlling communication between said receiving chamber and said barrel, means for momentarily opening said valve to permit communication between said receiving chamber and said barrel, said housing means having a second chamber extending generally parallel to the first chamber, a pressure regulator valve disposed in said second chamber, a passageway extending laterally from said storage chamber and communicating said storage chamber with said pressure regulating valve, a second passageway extending laterally from said receiving chamber and communicating said receiving chamber with said pressure regulating valve, said regulator valve being responsive to the pressure in the receiving chamber for automatically maintaining a substantially uniform pressure in said receiving chamber so long as the pressure in said storage chamber is as high as said receiving chamber pressure, whereby substantially the same fluid pressure is communicated to said barrel each time said normally closed valve is opened, without recharging said storage chamber until the pressure therein has diminished below a predetermined value.

2. A hand carriable self-contained pneumatic gun including a barrel through which shot is propelled, housing means including a chamber extending generally parallel to said barrel, means separating said chamber into a storage chamber adapted to contain a supply of air under pressure

and an adjacent receiving chamber communicable with said barrel, a normally closed valve controlling communication between said receiving chamber and said barrel, means for momentarily opening said valve to permit communication between said receiving chamber and said barrel, said housing means having a second chamber extending generally parallel to the first chamber, a pressure regulator valve disposed in said second chamber, a passageway extending laterally from said storage chamber and communicating said storage chamber with said pressure regulating valve, a second passageway extending laterally from said receiving chamber and communicating said receiving chamber with said pressure regulating valve, said regulating valve including a member normally held in its closed position by a predetermined pressure in the receiving chamber, and means for automatically opening said member when the pressure in said receiving chamber is below said predetermined pressure, to establish communication between said storage and receiving chambers, so as to maintain a substantially uniform pressure in said receiving chamber.
